INVENTOR

Thomas E. Brown

UNITED STATES PATENT OFFICE.

THOMAS E. BROWN, OF NEW YORK, N. Y.

HYDRAULIC TRANSMISSION.

1,327,080.

Specification of Letters Patent.

Patented Jan. 6, 1920.

Application filed April 7, 1919. Serial No. 288,161.

To all whom it may concern:

Be it known that I, THOMAS E. BROWN, a citizen of the United States, and a resident of the borough of Manhattan, in the city, county, and State of New York, have invented certain new and useful Improvements in Hydraulic Transmissions, of which the following is a specification.

This invention relates to improvements in that class of apparatus in which the power of a driving member is transmitted to a driven member by means of energy imparted to a liquid by the rotation of the driving member, said energy being in turn transmitted to a driven member and in which the liquid, after having acted on the driven member, is returned to the driving member and is circulated again and again continuously.

20 My copending application, Serial No. 261885, filed Nov. 9th, 1918, shows and describes means to convey the liquid discharged from the driven member to the driving member through a central chamber with rotation in the direction of rotation of the driving member, and so return to said member the energy remaining in the liquid, and the present invention refers more particularly to the conveyance of the energized liquid from the driving member to the driven member.

In this class of apparatus high efficiency is of the utmost importance to minimize the generation of heat, and to this end it is essential that the machine be reduced to the fewest elements by elimination of all details tending to produce friction and loss of hydraulic head, and that the actuating liquid be free to circulate with as few changes as possible from pressure to kinetic energy and vice versa, so that the heat generated will be as little as possible and within the capacity of simple means for conveying it away.

Heretofore it appears to have been thought that the energy passing from the driving member or driver to the driven member should be kinetic only and therefore that the outlet of the driver should be placed close up against the inlet of the driven member, with only a short annular space between but little if any longer than required for running clearance, or when this was not done, that any intervening space between the outlet of the driver and the inlet

of the driven member should be filled with 55 non-rotating guide vanes to guide the liquid from the driver to the driven member.

I have found that such constructions are inefficient and that higher efficiency is obtainable by conveying the centrifugal pressure, generated in the liquid by the driver, to the driven member as pressure energy without conversion to kinetic energy, while at the same time the rotational energy imparted to the liquid is conveyed to the driven 65 member as kinetic energy.

I accomplish this, and thereby the main objects of my invention, which are simplicity of construction, high efficiency, and avoidance of undue generation of heat, by 70 surrounding the driver and driven member by an unobstructed open circumferential pressure chamber of comparatively large area, through which the liquid passes from the driver to the driven member, and in 75 which the liquid rotates freely around the axis of the machine while under centrifugal pressure, and by rotating the walls of the chamber at a speed equal to or in excess of the speed of the liquid I am enabled to 80 reduce the friction of the liquid against the walls of the chamber until it is practically negligible.

Another object of my invention is to simplify the curvature of the vanes and thereby 85 still further increase the efficiency.

Another object is to provide a construction in which the outlet circumference of the driving vanes and the inlet circumference of the driven vanes may be of different diameters, whereby I am enabled to obtain better efficiency at higher ratios, or on the other hand may obtain substantial torque at 90 low ratios of driver speed to driven speed.

Another object of my invention is to still 95 further decrease friction by balancing the end thrusts, thereby also avoiding the necessity for expansive thrust bearings.

And still another object of my invention is to provide simple means for conveying 100 away the heat generated in the apparatus.

The means of accomplishing these and other objects will be better understood from the description and drawings.

Referring to the drawings:

Figure 1— is a side view, in partial section, of the preferred form of the machine, Fig. 2— is an end view in partial section,

Fig. 3— is a partial isometric edge view, and

Fig. 4— is a sectional diagram of a modified form.

5 Arrows indicate the direction of rotation, and also the direction of flow of the actuating liquid.

Similar reference numbers refer to similar parts in all the figures.

10 Referring to Fig. 1— A—A is the axis about which the machine revolves, and about which the moving parts are symmetrically disposed. 1— is the driving shaft which may be driven by any suitable means such 15 as a gas engine or electric motor. 2— is the driven shaft, and 3 and 4, bearings for these shafts respectively. 5— is a head, preferably bolted to the flange 6 of driving shaft 1 so as to rotate with said shaft and 7 is a 20 similar head. Heads 5 and 7 form the axial ends of the transmission and are connected by the peripheral rim 8 to which said heads are bolted, the heads 5 and 7 and rim 8 forming a liquid tight casing. On the in- 25 side of the heads 5 and 7 and circumferentially disposed around them are vanes 9 which are attached to and rotate with said heads and said rim 8, said heads 5 and 7 said rim 8 and said vanes 9 forming the 30 driving member 11 which, for brevity, I hereinafter call the "impeller". The head 7 is preferably provided with a stuffing box 12, gland 13 and packing 14. 16— is a disk which carries the vanes 17, (preferably pro- 35 vided with shrouds 10) and hub 18, the whole constituting the driven member 19, which, for brevity, I hereinafter call the "runner". Said hub 18 is secured to shaft 2 in any suitable manner as by key 23.

40 The vanes 9 of the impeller and vanes 17 of the runner terminate at their inner ends at a considerable distance radially from the axis and form the vortex chamber 20, which extends preferably the full axial length of the 45 machine between heads 5 and 7, said vortex chamber 20 being divided into two parts by the disk 16.

21, 21 are hubs integral with heads 5 and 7; said hubs form bearings for the inside 50 end of shaft 2 and are of suitable outside diameter to form with hub 18 a core to limit the inner radius of the vortex chamber. 15, 15 are spacing washers between cores 21 and hub 18, to reduce friction and 55 maintain the runner 19 in its central position. 22 is an unobstructed or open chamber extending circumferentially entirely around the machine and formed by the rim 8, heads 5 and 7 and the outer ends of the 60 runner vanes 17 and impeller vanes 9 and preferably extending the full axial length of the machine between the heads 5 and 7.

65 By "open chamber", I mean one unobstructed by vanes and circumferentially continuous but not open to the atmosphere.

24 is a light outer jacket preferably made of sheet metal and surrounding the impeller 11. Said jacket 24 is so secured to said impeller 11 as to leave a space between said jacket and said impeller, and so as to ro- 70 tate with said impeller.

25 are centrifugal vanes which may also act as spacers between jacket 24 and heads 5 and 7.

26 are peripheral openings circumferen- 75 tally spaced around said jacket.

27 are annular inlet openings in said jacket 24, said openings 27 being preferably concentric with the axis of the machine.

28 are pipes to supply cooling liquid to 80 said jacket 24.

29 is a circumferential receiver or catcher surrounding the outer casing 24 but free from it and fixed in position and which may be supported in any suitable manner as by 85 the floor or base of the machine.

30 is a pipe to draw the liquid from receiver 29.

Fig. 2— is an end view, in partial section, looking from the driven shaft end. 90 The upper left hand quadrant is a section on line A. A. B.—Fig. 1, showing the impeller vanes 9, and the upper right hand quadrant is a section on line A. A. C.—Fig. 1, showing the runner vanes 17—both quadrants 95 show in section the circumferential open chamber 22, and the vortex chamber 20.

Fig. 2— is drawn in this way so the rotations of the members as well as the rotation of the actuating liquid which with my construction are always in the same direction 100 will show in the same direction on the figure as indicated by the arrows.

The impeller vanes 9 preferably point at their inner ends *i. e.*, at the outer circumference of the vortex chamber 20, against the direction of motion and as they extend outward they curve in perpendicular planes until they become preferably radial at their outer ends. By perpendicular planes I mean 110 planes perpendicular to the axis. The runner vanes 17 curve inwardly in perpendicular planes and terminate at the circumference of the vortex chamber 20 and pointing in the direction of motion of the machine. It should be noted that with my construction the impeller vanes 9 and runner vanes 115 17 may have their curvature entirely in perpendicular planes and curvature in axial planes may be entirely avoided.

The machine is filled with a proper amount of any suitable actuating liquid such as water or oil, and the pressure and momentum induced in this liquid are used to convey power from the impeller to the 125 runner.

The operation is as follows:

When the driving shaft 1 with impeller 11 is rotated by the engine or motor, the vanes 9 set the liquid in rotary motion and a 130

hydraulic head is created in the actuating liquid which causes said liquid to circulate through the machine in the direction of the arrows, see Figs. 1 and 2. The liquid passes 5 from the impeller vanes 9 through the circumferential chamber 22 then inwardly through the runner 19 and reacts on the runner vanes 17, and sets up a torque and causes rotation of the runner and drives 10 shaft 2.

The actuating liquid passes from the runner vanes 17 into the vortex chamber 20, which it enters in the direction of rotation of the machine at a high velocity and whirls 15 around in said chamber, forming a vortex or whirlpool, while it traverses said chamber axially in both directions to the vanes 9 of impeller 11 which it enters in the direction of the rotation of the machine and circulates over again as shown and described 20 in my hereinbefore-mentioned copending application, Serial No. 261885, filed Nov. 9th, 1918.

By reference to the arrows in Fig. 2, 25 it will be seen that the actuating liquid in its passage through the machine always has a motion of rotation in the direction of the rotation of the machine, and never in the opposite direction, and therefore the momentum of the liquid entering the impeller assists the impeller and does not buck against the impeller and produce counter torque and consequent loss of efficiency.

The open circumferential chamber 22 is 30 an important feature of my invention as by its use I am enabled to accomplish the principal objects of my invention. By it I am enabled, as shown in Fig. 1, to place the vanes of the impeller and the runner in different coaxial planes, and, as shown in 40 Fig. 2, curve said vanes only in perpendicular planes, thus the construction as well as the flow of the liquid is simplified and the hydraulic frictional loss reduced.

45 The use of the circumferential chamber 22 enables the circumferential outlet of the impeller and inlet of the runner to be made of different diameters, thus the outlet of the impeller may have a smaller diameter than 50 the inlet of the runner as shown in Fig. 1, or may have a larger diameter as shown in Fig. 4, and obviously they may be made of equal diameter when desirable.

Referring to Fig. 4, 31 is a peripheral rib 55 or fin integral with rim 8. The fin 31 is preferably used when, as in Fig. 4, the impeller vanes are larger in diameter than the runner vanes. It may be used when desired in connection with the form shown in Fig. 1.

60 The value of this difference of diameter or radius of the impeller and runner vanes lies in the fact that the torque of the runner is partially a function of the difference of the peripheral speeds of the impeller and 65 runner vanes, and thus when the runner

vanes are larger in outside diameter than the impeller vanes as shown in Fig. 1, a given difference of peripheral speed is obtained with a less relative number of revolutions of the runner than when the said 70 vanes are of the same diameter. The converse is also true, and by using runner vanes of smaller diameter as shown in Fig. 4 substantial torque may be obtained even when the impeller and runner rotate at the same 75 revolutions per minute.

The principal value of the circumferential chamber 22 is in the transfer of the energy from impeller to runner with the least frictional loss, for the rotation of the 80 runner sets up a centrifugal counter head or pressure similar to the counter E. M. F. set up in an electric motor, and this counter head or pressure must be overcome by similar pressure set up in the impeller by its 85 rotation, and the chamber 22 permits of the transmission of this pressure directly to the runner without loss by conversion to kinetic energy. Also the rotational or kinetic energy imparted to the liquid by the impeller 90 is transferred to the runner with but little if any loss, for as indicated by the figures, the outer walls of said chamber rotate with a speed normally greater than the rotational speed of the liquid and hence any friction 95 between said liquid and said walls tends to add to and not to reduce the kinetic energy in said liquid.

It will be evident from the drawings that 100 all passages and spaces occupied by the actuating liquid are symmetrically disposed with reference to the central perpendicular plane, therefore the axial thrusts produced by the actuating liquid are equal in both axial directions and hence are balanced and 105 therefore friction is reduced and the use of expensive thrust bearings avoided.

The cooling features of my invention are 110 simple and easily understood from the drawings. The casing 5, 7, 8 being in rotation and with it the jacket 24, a cooling liquid, preferably water, is admitted by the pipes 28 to the inlets 27. Said liquid is set in rotation by the centrifugal vanes 25 and fills the space between jacket 24 and casing 115 5, 7, 8. The induced centrifugal pressure causes said liquid to escape through the peripheral openings 26, and it is caught in the stationary receiver 29 from which it may be conveyed away by pipe 30.

Thus a flow of liquid occurs over the surface of the casing 5, 7, 8, which carries away the heat generated in the apparatus. With small powers the heat generated will be proportionally small and air cooling may be 125 ample, and in such cases the pipes 28 and receiver 29 may be omitted and the peripheral openings 26 enlarged; the jacket 24 and vanes 25 then form a simple centrifugal fan. With still smaller powers the jacket 130

24 may be omitted and sufficient cooling effect be obtained by the rapid rotation of the apparatus in the air.

It should be noted that the machine, as shown in Figs. 1 and 4, may be transposed, i. e., power may be applied to rotate shaft 2, in which case the runner 19 becomes the impeller and casing 5, 7, 8, with vanes 9 becomes the runner. In this case, to obtain the best effect, the curvatures of the vanes should also be transposed.

Also it is obvious that the vanes at one or the other end of the impeller may be omitted if desired.

15 It should be specially noted that with my construction the actuating liquid is ejected from the impeller in perpendicular planes in an outward direction and that said liquid is received by the runner in other perpendicular planes in an inward direction, said directions in both cases having rotational components, and that a function of the circumferential chamber 22 and its walls is to change the outward direction of the motion of the liquid to an inward direction.

Now, having described my invention what I claim is:

1. The combination in a hydraulic transmission of an impeller having vanes at each end, a runner centrally placed between said vanes, a casing inclosing said vanes and said runner and an open chamber, formed by said casing, circumferentially surrounding said vanes and said runner.

35 2. The combination in a hydraulic transmission of an impeller having vanes at each end, a runner centrally placed between said vanes and a casing inclosing said vanes and said runner and rotatable with said impeller vanes.

40 3. The combination in a hydraulic transmission of an impeller having vanes at each end, a runner centrally placed between said vanes, a rotatable casing inclosing said vanes and said runner and an open chamber, formed by said casing, circumferentially surrounding said vanes and said runner.

45 4. The combination in a hydraulic transmission of heads forming the axial ends of said transmission, vanes on said heads, a runner centrally placed between said vanes, and a peripheral rim connecting said heads and forming an open chamber surrounding said vanes and said runner.

50 5. The combination in a hydraulic transmission of heads forming the axial ends of said transmission, vanes on said heads, a runner centrally placed between said vanes, a peripheral rim connecting said heads and forming an open circumferential chamber surrounding said vanes and said runner and a central vortex chamber extending axially between said heads.

6. In a hydraulic transmission, a driving

member and a driven member, one of said members having vanes at each end, said vanes disposed coaxially, the other of said members centrally placed between said vanes, a casing inclosing said members and said casing rotatable with one of said members.

7. In a hydraulic transmission, the combination of an impeller, a runner, an actuating liquid, a peripheral rim rotating with said transmission, and an open circumferential chamber, formed by said rim, and through which said liquid travels from said impeller to said runner.

8. In a hydraulic transmission, an impeller, a runner, an actuating liquid, a peripheral rim rotating with said transmission, an open circumferential chamber, formed by said rim, and a central vortex chamber through which said liquid travels from said runner to said impeller.

85 9. In a hydraulic transmission an impeller having vanes at each end, a runner centrally placed between said vanes, a peripheral rim forming a circumferential chamber surrounding said vanes and said runner and a central fin on said rim dividing said chamber into two coaxial parts.

10 10. The combination with a hydraulic transmission of a rotatable jacket surrounding said transmission and spaced therefrom, centrifugal vanes inside said jacket forming passages for the flow of a fluid over the surface of said transmission, and openings in the periphery of said jacket for the discharge of said fluid.

105 11. The combination with a hydraulic transmission of a rotatable jacket surrounding said transmission and spaced therefrom centrifugal vanes inside said jacket forming passages for the flow of a fluid over the surface of said transmission, openings in the periphery of said jacket for the discharge of said fluid, and annular inlets in the ends of said jacket for the admission of said fluid.

110 12. The combination with a hydraulic transmission of a rotatable jacket surrounding said transmission and spaced therefrom, centrifugal vanes inside said jacket forming passages for the flow of a liquid over the surface of said transmission, openings in the periphery of said jacket for the discharge of said liquid, inlets in the ends of said jacket for the admission of said liquid, and a non-rotating circumferential receiver for the discharged liquid.

120 13. In a hydraulic transmission, rotatable about an axis, an impeller, a runner, an actuating liquid, vanes on said impeller and vanes on said runner, said impeller vanes and said runner vanes disposed coaxially and having curvature only in planes perpendicular to said axis, a circumferential passage for said liquid from said impeller vanes

to said runner vanes and a central passage for said liquid from said runner vanes to said impeller vanes.

14. In a hydraulic transmission rotatable about an axis and containing an actuating liquid, an impeller adapted to discharge said liquid outwardly in perpendicular planes, a runner adapted to receive said liquid inwardly in perpendicular planes, and peripheral means rotating with said transmission adapted to change the outward motion of said liquid to an inward motion.

15. In a hydraulic transmission containing an actuating liquid, an impeller adapted to discharge said liquid outwardly in perpendicular planes, a runner adapted to receive said liquid inwardly in perpendicular planes and an open circumferential chamber adapted to change the outward motion of said liquid to an inward motion.

16. In a hydraulic transmission, an impeller and a runner, sets of vanes on said impeller and a set of vanes on said runner, said sets disposed coaxially and of unequal diameter and a circumferential chamber rotating with said transmission and adapted for the passage of an actuating liquid between said sets of vanes.

17. The combination with a hydraulic transmission of a jacket surrounding said transmission, a space between said jacket and said transmission and means to induce a flow of fluid through said space to cool said transmission.

35 18. The combination in a hydraulic trans-

mission of an impeller, a runner, a central vortex chamber, a disk dividing said chamber into two parts, an actuating liquid and means to guide said liquid into said parts and in the direction of rotation of said transmission.

19. The combination in a hydraulic transmission of an impeller having vanes at both ends, a runner centrally placed between said vanes, a disk on said runner, a central chamber divided into two parts by said disk, an actuating liquid and means to guide said liquid in said parts and in the direction of rotation of said transmission.

20. The combination in a hydraulic transmission of a driving member, and a driven member, one of said members having vanes at each end, said vanes disposed coaxially, the other of said members centrally placed between said vanes, a casing inclosing said members and an open circumferential chamber formed by said casing.

21. In combination with a hydraulic transmission, a stationary receiver surrounding said transmission and adapted to receive cooling liquid from the surface of said transmission.

22. The combination with a hydraulic transmission of a jacket surrounding said transmission, a space between said jacket and said transmission and centrifugal vanes to induce a flow of cooling fluid through said space.

THOMAS E. BROWN.
